Filed Mar. 11, 1974, Ser. No. 450,129

Term of patent 14 years

Int. Cl. D7—03

U.S. Cl. D7—151

FIG. 1 is a front elevational view of a spoon or similar article of flatware showing my new design;

FIG. 2 is a side elevational view thereof;

FIG. 3 is a rear elevational view thereof; and

FIG. 4 is a cross-sectional view taken on line 4—4 of FIG. 2 on an enlarged scale.

The design is intended for use with spoons, knives, forks and other articles of flatware.

I claim:

The ornamental design for a spoon or similar article of flatware, substantially as shown and described.
